STOCKING

Filed April 10, 1929

INVENTOR:
Alfred E. Ischinger,
BY W. G. & D. McNamee
ATTORNEYS.

UNITED STATES PATENT OFFICE.

ALFRED E. ISCHINGER, OF WYOMISSING, PENNSYLVANIA, ASSIGNOR TO BERKSHIRE KNITTING MILLS, OF WYOMISSING, PENNSYLVANIA, A CORPORATION OF PENNSYLVANIA.

DESIGN FOR STOCKING.

Application filed April 10, 1929. Serial No. 30,835. Term of patent 14 years.

To all whom it may concern:

Be it known that I, ALFRED E. ISCHINGER, a citizen of the United States, residing at Wyomissing, in the county of Berks and State of Pennsylvania, have invented certain new, original, and ornamental Design for Stocking, of which the following is a specification.

The drawing is a side elevation of a stocking embodying my design.

What I claim is:

The ornamental design for stocking, as shown.

In testimony whereof I affix my signature.

ALFRED E. ISCHINGER.
